(57) **CLAIM**

We claim the ornamental design for a chewing tobacco can with raised bottom section, as shown and described.

DESCRIPTION

FIG. 1 is a perspective view of the tobacco can according to my new design;

FIG. 2 is a top plan view of the tobacco can of FIG. 1 with the lid removed;

FIG. 3 is a top plan view of the tobacco can of FIG. 1 with the lid on the can;

FIG. 4 is a side elevation view of the tobacco can of FIG. 1; FIG. 5 is a bottom plan view of the tobacco can of FIG. 1; and,

FIG. 6 is a cross-sectional view of the tobacco can of FIG. 1 taken along line 6—6 of FIG. 5.
